UNITED STATES PATENT OFFICE.

SAMUEL HARVEY GARRETT, OF FORT WORTH, AND JOSEPH OWEN STAUDE, OF WEATHERFORD, TEXAS.

DERAILING-BLOCK.

1,280,437.

Specification of Letters Patent.

Patented Oct. 1, 1918.

Application filed February 19, 1918. Serial No. 218,143.

To all whom it may concern:

Be it known that we, SAMUEL HARVEY GARRETT and JOSEPH OWEN STAUDE, citizens of the United States, residing at Fort Worth and Weatherford, respectively, in the counties of Tarrant and Parker, respectively, and State of Texas, have invented certain new and useful Improvements in Derailing-Blocks, of which the following is a specification.

Our invention relates to new and useful improvements in derailing blocks such as are used by railroads, and it has particular reference to a device of this character which can be easily and quickly clamped or fastened to one of the rails on a railroad track, our principal object being to provide a derailing block which is portable, of comparatively light weight and can be readily locked to or removed from a rail as occasion demands.

In the carrying out of our invention we provide a block adapted to lie flat on the head of the rail, the top of the block being arched to raise the wheel of a car from the rail and having a flange for diverting the wheel from the railroad track as it takes the arch. The block proper is clamped to the web of the rail beneath the head by a cam-shaped lever arm arranged so that a movement of the arm horizontally in either direction is sufficient to fasten the block to or remove same from the rail.

Our invention will be more fully and clearly understood by reference to the accompanying drawing and the following description taken therewith:

Figure 1 is a side elevational view of a derailing block, embodying our invention arranged on the rail.

Fig. 2 is a top or plan view of the same.

Fig. 3 is a side elevational view taken from the side opposite to that shown in Fig. 1.

Fig. 4 is a cross-sectional view, taken on the line 5—5, of Fig. 2, and

Fig. 5 is a top view of the cam-shaped lever arm for clamping the block to the rail.

Referring to the drawings, 1 represents the right hand rail of a railroad or railway track to and on which the derailing block embodying our invention is to be attached. This derailing block has a body 2 extending some distance beyond the inside edge of

the rail 1 and to its under surface is pivoted a cam lever 3. The body 2 rests upon the head of rail 1 and extends upward therefrom in the form of a flange 4, the inner face of which is preferably straight and extends at an angle to the rail from a point beyond the inner side of said rail to a point directly above the outer side of the head of said rail. The block 2 has a downwardly projecting lug or bearing 5 extending adjacent to the inner side of the head of the rail and forming the pivotal support for cam lever 3, the cam of said lever being held to the under face of said bearing by a screw bolt 6 traversing an opening 7 arranged eccentrically of the cam of the lever and screwing into said lug 5. The bearing edge of the cam lever 3 is ridged or corrugated as at 8 to more tightly grip the web of the rail when the block is locked to position. The upper surface of the cam portion of the lever 3 is also provided with a wedge-shaped projection 9 fitting under the head of the rail 1 to clamp the block down upon said rail head when said cam lever 3 is moved horizontally to bite into the web of the rail.

The outer side of block 2 is provided with one or more downwardly extending hook-shaped projections 10 which fit around and under the head of the rail to lock the block to the rail.

The upper face of the block 2 has on its outer side a rounded or arched projection or cheek 11 resting on the top of the rail head. This cheek 11 receives the rim of the wheel and guides said rim across the rail in the derailing operation. The flange of the wheel is deflected into the channel 12 of the block 2 between the flange 4 and cheek 11 and said flange 4 forms the bearing against which the flange of the wheel rides as said flange travels over the channel 12 of the block.

If desired the block 2 may be provided with a handle 13 whereby it may when released from the rail be carried to a new point of use or transported by a brakeman to the train. The block is of peculiar usefulness in preventing rear end collisions in that it adds to the usual safeguard of a brakeman and his flag an additional safeguard in that if the approaching train fails to stop on the brakeman's signal the block in position will derail the oncoming train.

Having described the nature and objects of our invention, what we claim as new and desire to secure by Letters Patent, is—

1. In a derailing block, a body having its upper face contoured to receive and guide the rim and flange of a wheel, a means for hooking said body to the head at one side of the rail, and a cam lever pivotally mounted on the block at the opposite side of the rail, said lever arranged to swing horizontally under the head of the rail to bite into the web of the rail and to clamp the block down upon the head of the rail.
2. In a device of the character described an arched block having an upwardly extending flange, the inner face of the up-

wardly projecting flange extending in a relatively straight line at a more or less acute angle to the rail, and having downwardly extending hook-shaped projections curved under the head part of the rail in combination with a cam-shaped lever arm pivotally connected to the under portion of the block to clamp the block to the web of the rail, said lever arranged to swing horizontally under the head of said rail to clamp the block down upon the head of the rail.

In testimony whereof we have signed our names to this specification.

SAMUEL HARVEY GARRETT.
JOSEPH OWEN STAUDE.
